UNITED STATES PATENT OFFICE.

ERNST F. HOFMANN, OF NEW YORK, N. Y.

PESSARY.

SPECIFICATION forming part of Letters Patent No. 307,944, dated November 11, 1884.

Application filed April 10, 1884. (No model.)

To all whom it may concern:

Be it known that I, ERNST F. HOFMANN, a citizen of the United States, residing at New York, in the county and State of New York, 5 have invented new and useful Improvements in Pessaries, of which the following is a specification.

This invention relates to an improvement on the pessary described in Letters Patent No. 65,382, granted to me June 4, 1867.

The peculiar and novel form and construction of my new pessary is pointed out in the following specification and claim, and illustrated in the accompanying drawings, in which—

15 Figure 1 represents a plan or top view. Fig. 2 is a longitudinal vertical section in the plane $x x$, Fig. 1. Fig. 3 is a front view.

Similar letters indicate corresponding parts.

In the drawings, the letter A designates my 20 pessary, which is made of hard rubber or any other suitable material. Its rear portion, a, rises up to a level considerably above the level of the front portion, b, (see Fig. 2,) forming an abrupt ridge, c, round the rear portion of 25 the opening B of the pessary, said ridge extending about half-way round the opening. (See Fig. 1.) The rear and front surfaces, d e, of the pessary are concave, the same as in the pessary described in Patent No. 65,382; but 30 while the side surfaces in the old pessary are

convex, the side surfaces, f g, of my new pessary are concave, as shown in Fig. 1. When the pessary is in position, the flesh of the surrounding parts enters the concavities of the side surfaces, f g, and by these means the 35 pessary is effectually prevented from turning round, and it is consequently retained in the required position. The upper edge of the ridge c is also concave, as shown in Fig. 3, and since the rear side of the uterus settles down 40 into this concavity, an additional hold is given to the pessary, and at the same time no undue pressure is exerted on the uterus.

I distinctly disclaim in this application the pessary shown and described in Patent No. 45 65,382.

What I claim as new, and desire to secure by Letters Patent, is—

A pessary provided with concave sides f g, in addition to concave rear and front surfaces, 50 d e, and the ridge c, substantially as shown and described.

In testimony whereof I have hereunto set my hand and seal in the presence of two subscribing witnesses.

ERNST F. HOFMANN. [L. S.]
